Primary Examiner—A. Hugo Word*Assistant Examiner*—Lavone D. Tabor*Attorney, Agent, or Firm*—Richard B. O'Planick; Lisa B. Riedesel[57]*CLAIM

The ornamental design for a handle for scrub brush, as shown and described.

DESCRIPTION

FIG. 1 is a top left front perspective view of a handle for scrub brush showing our new design;

FIG. 2 is a top plan view thereof;

FIG. 3 is a front elevational view thereof; the rear elevational view being a mirror image; and,

FIG. 4 is a right side elevational view thereof; the left side elevational view being a mirror image.

The broken lines are for illustrative purposes only and form no part of the claimed design.
